ACCELERATOR TARGET HOLDER

Carroll M. Gordon, San Pablo, and Charles A. Corum, Berkeley, Calif., assignors to the United States of America as represented by the United States Atomic Energy Commission

Application November 26, 1952, Serial No. 322,654

14 Claims. (Cl. 250—49.5)

1 This invention relates to particle accelerators and more particularly to apparatus employed therewith for the purpose of accurately positioning target material in the path of the beam.

In the irradiation of small samples in a cyclotron or other accelerator, it has been found convenient to dispose such samples within a metal foil container having the shape of a relatively flat dish. In providing a mechanism for mounting the dish in the path of the beam, several problems are encountered. It is important that such mechanism permits rapid removal of the material following irradiation, since many such target materials exhibit a brief half-life (rapid loss of radioactivity) and the interval of exposure of the operator should be a minimum.

In use portions of the mechanism adjacent the target become radioactively contaminated so that their replacement necessitates due consideration to the simplicity and cost factors as well as interchangeability of such parts. In addition to the foregoing requirements, means must be provided for the circulation of coolant through as much of the entire apparatus as possible.

The present invention therefore is an improved target apparatus characterized by the named advantages and which are more specifically identified in the following objects.

It is accordingly a principal object of the invention to provide accelerator target apparatus that may be quickly positioned for irradiation adjacent accelerator structure and as readily removed therefrom.

Another object of the invention is to provide accelerator target apparatus having a fluid-cooled portion for relatively permanent mounting on the accelerator wall structure and a target holding and fluid-cooled portion which is quickly removable from said first portion.

Another object of the invention is to provide a generally two-component target apparatus in which the removable component is always pre-aligned when in assembled relation with the fixed component.

A further object is to provide accelerator target apparatus including a stationary, vacuum-tight component adapted to be mounted on the accelerator wall and a removable target bearing component insertable therein and surrounded by a circulating fluid coolant.

An additional object is to provide a removable target holder including relatively movable members adapted to form and seal disk elements into a substance enclosing container, to maintain said container in a predetermined aligned position of

2 irradiation and upon subsequent relative movement of said members to release said container for gravity discharge.

Other objects and advantages of the invention will be obvious and will be apparent from the following specification and accompanying drawings wherein:

Figure 1 is a side view chiefly in section showing the target apparatus of this invention in position upon the wall of a cyclotron tank, for example;

Fig. 2 is a vertical sectional view taken on line 2—2 of Fig. 1;

Fig. 3 is a top view of Fig. 1, partly in section as indicated by line 3—3 of the latter figure;

Fig. 4 is an end elevation of Fig. 1 as viewed from the right side of the latter and somewhat reduced in scale; and

Fig. 5 is a side view of the removable portion of the target apparatus of Fig. 4 as viewed from the left side thereof.

The design of the individual components and their functional relation will be more readily appreciated by considering first, the removable target carrier of the target apparatus shown per se in Fig. 5 and in position with the stationary components for irradiation in the remaining figures which depict, particularly in the sectional views, the details of construction.

Accordingly, in Fig. 1 such target carrier is shown as including a cylindrical mandrel 5 secured as by engaging threaded surfaces to a cylindrical mandrel body 6 of slightly greater diameter, the two parts named presenting a continuous cylindrical bore on the inner surfaces thereof. The end of mandrel 5 opposite the body 6 is formed with an integral cap portion 7 which is apertured for a diameter somewhat less than that of the continuous inner bore referred to above, and is inwardly shouldered at 8 to provide a mandrel ledge for a purpose later to be described. Smoothly fitting within the inner bore of mandrel components 5 and 6 is an inner cylinder 9, the inner end of which adjacent the ledge 8 is cut away at a suitable angle to form a swaging surface 10 adapted upon travel of the cylinder 9 to the left, as shown in Fig. 1, and into peripheral engagement with a pair of foil disks disposed between surface 10 and ledge 8 to deform the circumference of said disks and effect a seal thereby. An annular seal 11 surrounding cylinder 9 and disposed in a suitable recess in mandrel body 6 precludes the loss of vacuum through these inter-fitting cylindrical surfaces as will later appear.

For retracting cylinder 9 from the mandrel components 5 and 6, there is provided a cross-head 12 having a seal receiving annular recess 13 surrounding a central bore extending inwardly from one end thereof. Such bore is peripherally stepped to receive a similarly stepped outer end of cylinder 9 around which the seal in recess 13 exerts sealing pressure; also an adjacent outer stepped portion of greater diameter receives a correspondingly threaded portion of cylinder 9, the two parts when assembled as shown in Fig. 1 constituting an essentially hermetically sealed unit. Transverse bores 14 and 15 are provided in the cross head 12 and lead from suitable integral external conduits 16 and 17 to the interior of cylinder 9, bore 15 communicating with the open-ended tube 18 which is axially mounted in crosshead 12 for the continuous circulation of a coolant such as water therethrough.

Crosshead 12 is provided with a portion adapted to have mechanical connection with suitable actuating means; such portion may have the form of an integral tongue 19 extending diametrically thereacross and for a sufficient axial extent as to provide the connection mentioned. The latter preferably has the form of a bar 20 bifurcated at its upper end to receive tongue 19 and pivotally connected thereto as by pin 21 secured in one of the bifurcations by set screw 22.

Closely surrounding the outer portion of mandrel body 6 is a suitably apertured handle 23 extending downwardly in generally parallel relationship with bar 20 and rigidly united to body 6 by suitable means such as an elongated set screw 24 threaded into the surrounding portion of said handle.

Interconnection of bar 20 with handle 23 to effect lateral movement of inner cylinder 9 may be accomplished as follows. Handle 23 and also bar 20 are provided with elongated central slots 25 and 26 to receive the opposite ends of a link 27, which ends are suitably pinned to the adjacent handle and bar at 28 and 29 and retained by respective set screws 30 and 31. A compression spring 32 may be confined between the central portions of bar 20 and handle 23 by any suitable retainers, such as the inwardly extending disks 33, welded for example, to these members. Pivoted on a pin 34 extending transversely of bar 20 below spring 32 and retained by set screw 35 is a distance piece 36 in the form of a bell crank, the shorter leg of which terminates in a curved contact surface 37 and the longer leg 38 of which, in the position shown in Fig. 1, is disposed in the plane of bar 20 and may be retained in such position by means of a knurled set screw 39 threaded into bar 20 so that its inner end frictionally engages leg 38. A bell crank shaped stop 40 having its longer leg 41 extending in general parallelism with handle 23 has its shorter leg 42 disposed in a slot 43 in handle 23 and is retained therein by a pivot pin 44 secured in such handle by a set screw 45. A stop screw 46 threaded into handle 23 above the slot 43 and in alignment with leg 38 and transversely of the upper end of leg 41 is provided with a slotted head, as shown, for arcuate adjustment of the leg 41 which serves to precisely vary the spacing between the lower end of handle 23 and that of bar 20 as to which reference will later be made.

Prior to proceeding with an explanation of the clamping action upon the superposed disks previously referred to, it is desired to call attention to a structural feature of considerable significance in the machining of the left end of man-

drel 5, as shown in Fig. 2. It will be observed that the wall of mandrel 5 slightly to the right of cap portion 7 and ledge 8 has been slotted to provide an entrance and exit passage 47 for the disks mentioned earlier and the formed container, respectively; such passage may be about any radius of symmetry but is peripherally about such a radius extending normally to the plane of bar 20 and handle 23 so that the disks may be loaded and following irradiation discharged from a position to one side of the device as a whole. Further such passage, as will be seen in Fig. 2, is of such arcuate extent as to comprehend a projected diameter so that the width of the slot for its entire length radially of mandrel 5 is that of a diameter thereof. From the foregoing, it will be seen that when the removable component of the target apparatus (Fig. 5) has been removed from its position of irradiation adjacent the accelerator wall (Fig. 1), knurled screw 39 may be rotated to release bell crank leg 38 and the latter then swung counterclockwise to the dotted line position shown.

Thereafter on bringing bar 20 to a position approaching handle 23 and thereby compressing spring 32 the inner cylinder 9 will move outwardly, Fig. 1, leaving a space between the end thereof and ledge 8 of mandrel 5. A receptacle in the form of a shallow dish 48 may now be introduced into peripherally supported position upon the swaging surface 10 of inner cylinder 9, the material to be irradiated having been previously placed in said dish or immediately thereafter following insertion. A flat cover disk 49 is then inserted into the mandrel 5 through the passage 47 and the manual pressure which confines bar 20 and handle 23 in their dotted line position, Fig. 5, is now released, allowing the swaging surface 10 to closely approach ledge 8 and thereby clamp or seal the peripheral portion of dish 48 to the adjacent portion of disk 49. Adjustment of stop 46 prior to this operation is necessary when the thickness of the foil, for example, is different from that employed in previous operations. It will be appreciated that the clamping action should not be excessive or an imperfect seal may result.

In positioning the portable target component above described so that the same will be in accurate alignment with the beam of particles and thereby irradiated, in addition to the alignment requirement it is desirable that the temperature gradient between the cyclotron wall structure and the portable target holder is as great as possible. Accordingly, provision has been made in the design of the stationary component of the target apparatus which is mounted on the cyclotron wall for the maintenance of three temperature zones decreasing in value from the cyclotron tank outwardly. In the embodiment illustrated herein it has been found expedient to provide three concentric structures which are disposed in relatively rigid insulating relationship and each of which has such positive coolant provisions as experimentation has been found to be necessary.

Referring therefore to Figs. 1 and 3 of the drawing, it will be observed that there has been provided an innermost collimating plate 50 of somewhat massive proportions disposed in vacuum tight relation against the face of the tank 52 and bolted thereto by peripheral bolts 53 passing through suitable flange apertures and thence into threaded recesses in the tank. An annular sealing ring 54 of suitable insulated ma-

terial disposed in a corresponding recess in the face of plate 50 adjacent tank 52 insures a vacuum tight seal thereagainst. Centrally of collimating plate 50 there is provided a collimating exit aperture 55 defined by an inverted cone 56 extending outwardly for a substantial distance and bounded by an outer cylindrical wall 57. This latter wall furnishes an additional continuous surface through which an adjacent intermediate flange plate 58 may be hermetically sealed through a suitable annular gasket 59 disposed in a corresponding recess in an inner cylindrical bore of said plate 58 corresponding in diameter to said cylindrical wall 57. Said intermediate plate 58 has also a peripheral surface disposed in a plane parallel with the surface of tank 52 which is closely maintained against the parallel outer surface of collimator plate 50 by means of bolts 62 passing therethrough into threaded recesses in such collimating plate, there being an intermediate circular gasket 63 disposed in vacuum-tight relation between the closely abutting plate surfaces. As will be seen in Fig. 1, intermediate flange plate 58 is cut away adjacent the proximate wall of collimating plate 50 for a substantial radial extent beyond the cylindrical boundary of cone 56 and such space provides a coolant chamber for the spaced metallic surfaces which is connected through passages 64 and 65 with external conduits 66 and 67 through which cooling water may be circulated. Thus it will be seen that intermediate flange plate 58 will be maintained at a lower temperature than that of the cyclotron aperture adjacent collimating plate 50.

Adjacent intermediate plate 58 and maintained in vacuum-tight relation therewith is an outer flange plate which provides two additional zones of reduced temperature gradients. Such outer flange plate, which is indicated at 68 on the drawing, is spaced from intermediate plate 58 by an annular ring 69 of resilient insulating material having an I-shaped cross section, the oppositely disposed recesses of which provide seats for appropriate annular vacuum seals 70, while a third seal is disposed in surrounding relation to insulator 69 and, in turn, is seated in a U-shaped annular recess 71 of the outer flange plate.

A desirable feature of the invention resides in a pair of spaced vacuum-tight windows 73 and 74 made of metal foil, for example, the inner window 73 of which has its peripheral portion sealed by contact with adjacent annular ring 70, while a similar ring 75 seated in a recess in plate 68 similarly seals the outer window. A ring-shaped spacer 76 provided with diametric bores leading into the space between the windows 73 and 74 and aligned with bores 77 and 78 in plate 68 may serve conveniently to convey helium gas to the space between such windows and at a somewhat higher pressure than that of the water circulated through the intermediate flange plate in order to lessen the likelihood of damage to the vacuum seals mentioned. Outer flange plate 68 is suitably secured to intermediate flange plate 58 by suitable spaced bolts 79 threaded into recesses in plate 58 and surrounded by cylindrical type insulators within the apertures in plate 68 as will be seen in Fig. 3.

Outer flange plate 68 is also provided with a radial bore 81 through which helium gas at a somewhat higher pressure than that in bore 77 may be supplied by an integral conduit 82 into the interior of the central cylindrical bore 83 into

which the mandrel body 6 is received, as shown in Fig. 1. Such helium supply is not intended to provide the cooling effect of the arrangements previously described as such action has been found not to be necessary. However, it is of value chiefly in scavaging the interior central bore 83 following irradiation and withdrawal of the removal of target component as described, after which the supply of gas is cut off and later re-established as needed.

Reference is now made to the means for securing the removable component of the target apparatus within the central bore 83, as shown in Fig. 1. Such arrangement may conveniently take the form of an integral or attached ear 84 extending outwardly from the peripheral cylindrical wall of outer flange plate 68 and provided with an aperture therethrough of slightly greater diameter than set screw 24. It is preferable to cut away the lateral wall of ear 84 to provide a passage merging with the named aperture to provide ingress for the set screw 24 into the slot thereby formed and in this way to definitely establish the rotative position of irradiation of the portable assembly as described.

It is further desirable to prevent loss of helium gas through the cylindrical surfaces of outer flange plate 68 and mandrel body 6 by disposing a vacuum sealing ring 85 in a suitable recess contiguous the central bore 83, as shown in Figure 1.

Accordingly, the invention is not intended to be limited to the embodiments as shown, but on the contrary is intended to cover such modifications and changes as are comprehended within the scope of the appended claims.

What is claimed is:

1. Accelerator target apparatus comprising a fluid-cooled, beam collimating flange assembly adapted to be hermetically mounted on the exit wall of an accelerator, said assembly including a relatively massive, conically apertured wall flange adjacent the exit beam of said accelerator, an intermediate flange plate maintained in peripherally sealed relation with said wall flange and having a substantial surface area nearest the latter flange, sufficiently spaced therefrom to provide a coolant chamber; and conduit means connected to said chamber for the circulation of a fluid coolant therethrough.
2. Accelerator target apparatus comprising a fluid-cooled, beam collimating flange assembly adapted to be hermetically mounted on the exit wall of an accelerator, said assembly including a relatively massive, conically apertured wall flange adjacent the exit beam of said accelerator, an intermediate flange plate maintained in peripherally sealed relation with said wall flange and having a substantial surface area nearest the latter flange, sufficiently spaced therefrom to provide a coolant chamber, and an outer cylindrically apertured flange plate insulating secured to said intermediate flange plate.
3. The combination of elements defined in claim 2 and including fluid conduit means connected to said outer flange plate for the circulation of a fluid coolant therethrough.
4. The combination of elements defined in claim 2 and including a pair of thin-walled foil sheets disposed in parallelism across the cylindrical aperture in said outer flange plate, means for peripherally sealing said sheets and fluid conduit means communicating with the space between said sheets.
5. The combination of elements defined in claim 2 and including an annular insulating seal

of substantial axial and radial extent disposed between said intermediate plate and said outer plate.

6. Accelerator target apparatus comprising a fluid-cooled, beam collimating flange assembly adapted to be hermetically mounted on the exit wall of an accelerator, said assembly including a relatively massive, conically apertured wall flange adjacent the exit beam of said accelerator, an intermediate flange plate maintained in peripherally sealed relation with said wall flange and having an annular recess in a plane surface normal to the aperture of said wall flange and remote from the latter, an annular insulating seal adapted to resist both axial and radial pressure disposed in said recess and an outer, cylindrically apertured flange plate having an annular extension disposed in said recess in pressure transmitting relation to said seal and means disposed peripherally of said outer flange plates for uniting the same into a relatively rigid assembly.

7. The combination of elements defined in claim 6 and including a pair of thin-walled foil sheets disposed in parallelism across the cylindrical aperture in said outer flange plate, means for peripherally sealing said sheets and fluid conduit means communicating with the space between said sheets.

8. The combination of elements defined in claim 6 and including a generally cylindrical target holder disposable in hermetically sealed relation in the cylindrical aperture of said outer flange plate.

9. The combination of elements defined in claim 6 including target holder retainer means integral with said outer flange plate, and a generally cylindrical target holder disposable in hermetically sealed relation in the cylindrical aperture of said outer flange plate and maintained in irradiating position by said retainer means.

10. The combination of elements defined in claim 6 including target holder retainer means integral with said outer flange plate and projecting outwardly therefrom, and a generally cylindrical target holder disposable in hermetically sealed relation for a substantial distance into the cylindrical aperture of said outer flange plate and maintained in irradiating position by said retainer means.

11. In accelerator target apparatus a target

holder comprising a generally cylindrical hollow mandrel having an end portion terminating in an inner peripheral ledge of less diameter than the major internal diameter of said mandrel, an inner cylinder sealingly disposed in the inner wall of said mandrel, said cylinder having an inclined peripheral end portion movable into swaging contact with said ledge for edge sealing of a pair of foil disks inserted therebetween, said mandrel being provided with a lateral slot in a wall portion thereof of slight axial displacement from said ledge for insertion and withdrawal of said disks.

12. The combination of elements defined in claim 11 and including a cross-head connected to said cylinder for moving the latter relative to said mandrel and fluid coolant means connected to said cross-head including a tube extending axially to the vicinity of said disks for cooling the latter during irradiation thereof.

13. The combination of elements defined in claim 11 and including a stationary bar secured to said mandrel, a cross-head connected to said cylinder, and a handle pivoted to said cross-head and having a link connection with said bar whereby relative movement of said bar to said handle is effective to move said cylinder axially of said mandrel.

14. The combination of elements defined in claim 11 and including a stationary bar secured to said mandrel, a cross-head connected to said cylinder, a handle pivoted to said cross-head and having a link connection with said bar and adjustable means extending between said handle and said bar for adjusting the spacing between said ledge and the peripheral end portion of said cylinder.
